(57) **CLAIM**

The ornamental design for an electronic display for a wearable device presenting a graphical user interface, as shown and described.

DESCRIPTION

FIG. 1 is a front view of a first embodiment of an electronic display for a wearable device presenting a graphical user interface, showing our new design;

FIG. 2 is an enlarged front view of the first embodiment thereof;

FIG. 3 is a front view of a second embodiment thereof;

FIG. 4 is an enlarged front view of the second embodiment thereof;

FIG. 5 is a front view of a third embodiment thereof;

FIG. 6 is an enlarged front view of the third embodiment thereof;

FIG. 7 is a front view of a fourth embodiment thereof;

FIG. 8 is an enlarged front view of the fourth embodiment thereof;

FIG. 9 is a front view of a fifth embodiment thereof;

FIG. 10 is an enlarged front view of the fifth embodiment thereof;

FIG. 11 is a front view of a sixth embodiment thereof;

FIG. 12 is an enlarged front view of the sixth embodiment thereof;

FIG. 13 is a rear view thereof;

FIG. 14 is a left side view thereof;

FIG. 15 is a right side view thereof;

FIG. 16 is a top view thereof; and,

FIG. 17 is a bottom view thereof.

The broken line showing of the electronic display for a wearable device presenting a graphical user interface is for the purpose of illustrating portions of the electronic display

(Continued)

for a wearable device presenting a graphical user interface and forms no part of the claimed design.
